UNITED STATES PATENT OFFICE

146,450

DESIGN FOR A COMBINED CIGARETTE CONTAINER AND ASH TRAY

Carl M. J. Ornot, Charleroi, Pa.

Application March 8, 1946, Serial No. 127,236

Term of patent 14 years

(Cl. D85—2)

To all whom it may concern:

Be it known that I, Carl M. J. Ornot, a citizen of the United States, residing at Charleroi, in the county of Washington and State of Pennsylvania, have invented a new, original, and ornamental Design for a Combined Cigarette Container and Ash Trays, of which the following is a specification reference being had to the accompanying drawing, forming a part thereof.

I claim:

The ornamental design for a combined cigarette container and ash tray, as shown.

CARL M. J. ORNOT.
